UNITED STATES PATENT OFFICE.

WILLIAM DORTON, OF LEADWOOD, MISSOURI.

JIG.

1,391,531.

Specification of Letters Patent. Patented Sept. 20, 1921.

Application filed August 19, 1919. Serial No. 318,458.

To all whom it may concern:

Be it known that WILLIAM DORTON, a citizen of the United States of America, residing at Leadwood, in the county of St. Francois and State of Missouri, has invented new and useful Improvements in Jigs, of which the following is a specification.

The object of the invention is to provide a jig for the separation of metal bearing ores by the gravity process wherein a more complete, satisfactory and expeditious independent separation of the concentrates and middlings may be effected under conditions minimizing the cost as to the mechanism and labor, and to this end the invention 10 consists of a construction, combination and relation of parts hereinafter specifically set forth, it being understood that changes in form and proportion may be resorted to, 15 within the scope of the claims without departing from the principles involved.

In the drawing:

Figure 1 is a view of the complete machine.

Fig. 2 is a longitudinal sectional view of the same taken centrally through one of the series of the compartments.

Fig. 3 is a transverse section on the plane indicated by the line 3—3 of Fig. 2.

Within a suitable casing, preferably rectangular in plan there is arranged a plurality of longitudinal series of compartments, of which two are shown in the drawing, separated by a longitudinal partition 30 10, said compartments being numbered 11, 12, 13 and 14 and separated from each other and from a tailing apron 15 by the transverse walls or partitions 16, 17, 18 and 19 which have their upper edges located below 35 the upper edges of the side walls 20 and the longitudinal partition wall 10 at graduated distances. In other words, the transverse separating partitions between consecutive compartments of each series constitute 40 45 baffles or obstacles over which the material in one compartment flows into the next compartment and are of graduated heights, decreasing toward the outlet or tail end of the series. As a simple and economical construction of the framework constituting the 50 casing with its partitions and compartments into which the interior of the casing is divided, the drawing shows the extremities of the partitions mortised into the walls of the 55 casing and engaged by vertical bolts 21, a similar construction being contemplated in

the joints between the transverse walls and the intermediate longitudinal wall, and transverse bolts 22 connecting the side walls of the casing adjacent to the planes of said 60 transverse walls.

The material is fed to the initial or concentrate compartments 11 of the series by means of launders or chutes 23 and located within said compartments or bins are the 65 concentrate cups 24 and outlets 25 for the powdered concentrates, the other compartments 12 to 14 inclusive of each series having similar concentrate cups and outlets. Screens 26 are arranged respectively in the 70 initial and succeeding compartments or bins of each series and at the bottoms of the compartments are arranged hatches 27 and 28 located respectively to receive concentrates and middlings passing through the 75 screens.

At one end of the casing containing the series of concentrate and middlings compartments, upon a suitable extension 29, is mounted a drive shaft 30 having a belt 80 pulley 31 and carrying eccentrics 32 of which the straps or yokes are operatively connected with 35 and 36 operating respectively in the cylinders or boxes 37 and 38 located in the partitions respectively separating the initial and second compartments and the third and fourth compartments of each series. Said boxes or cylinders are open ended for communication respectively 85 with said compartments and the movement 90 of the pistons therein serves to cause a sufficient agitation of the contents to accelerate the separation and induce the prompt precipitation of the concentrates and middlings. The piston rod common to the two 95 plungers of each series is preferably divided at an intermediate point and fitted with a coupling 39 to facilitate the removal for cleansing purposes, and intermediate bearings 40 may be located on transverse braces 100 41 spanning the compartments to prevent sagging of the intermediate portions of the piston rod. Moreover, packing boxes 42 and 43 may be arranged respectively in the end 105 wall of the casing and the transverse wall between the compartments 12 and 13 for the passage of said piston rods.

In practice it is preferable to construct each piston or plunger of a block 44 of wood or equivalent material faced with iron or 110 other suitable metal plates 45 secured in place by cross bolts 46.

Preferably the compartments are provided with inclined floors 47 so as to produce a hopper-like arrangement leading to the hatches to facilitate the discharge of the material. The water inlet 48 may be arranged in the branched form indicated in Figs. 1 and 2 at the front end of the apparatus.

In the operation of the jig, water is admitted through the inlet 48, the flow being permitted until it rises to the height of the barriers, when the operation of the pistons affects an agitation of the water, causing it to flow over the upper edges of the barriers. The greater intensity of the flow is, however, adjacent the longitudinal partition 10 and there is a tendency to deflect the concentrates toward the side walls so that they may be deposited in the cups 24, the concentrate and middlings passing through the screens being deflected toward the hatches 27 by the inclined hopper like floors 47. In each succeeding compartment some of the concentrates and middlings left from the operation in the preceding compartment are removed until finally when the water passes over the tailing apron practically all of the concentrates and middlings are removed.

The invention having been described, what is claimed as new and useful is:

1. An apparatus for the purpose described having a series of consecutively available concentrate and middlings compartments provided with separating screens disposed adjacent the tops of said compartments and

separated by transverse barriers of graduated heights, concentrate cups disposed at the upper edges of the barriers and above the planes of the screens, a feed launder and a tailing apron operatively disposed with reference to the concentrate and terminal middlings compartments, a bottom outlet hutch in each compartment, and agitating means arranged between pairs of adjacent compartments in a plane substantially intermediate between the planes of the concentrate cups and the outlet hatches.

2. An apparatus for the purpose described having a series of concentrate and middlings compartments provided with separating screens disposed adjacent the tops of said compartments and separated by transverse barriers of graduated heights, the screens being located successively in relatively lower planes in said compartments, concentrate and middlings discharge cups located in said compartments above the planes of the screens and adjacent the upper edges of the barriers, concentrate and middlings hatches located respectively in said compartments adjacent the bottoms thereof, the compartments having hopper shaped floors leading to the hatches, and agitating means for agitating the contents of each compartment and disposed in a plane substantially intermediate between the planes of the said discharge cups and the said hatches.

In testimony whereof he affixes his signature.

WILLIAM DORTON.
